MOTION-PICTURE CAMERA

Frederick G. Knowles, Rochester, N. Y., assignor to Eastman Kodak Company, Rochester, N. Y., a corporation of New Jersey

Application December 24, 1954, Serial No. 33,672

Term of patent 14 years

(Cl. D61—1)

Fig. 1 is a perspective view of a motion-picture camera showing my new design and showing portions of the front, top and side; and

Fig. 2 is a perspective view of the motion-picture camera shown in Fig. 1 taken from an opposite viewpoint and showing the rear, top and the side opposite from that shown in Fig. 1.

I claim:

The ornamental design for a motion-picture camera, as shown.
